CLAIM

The ornamental design for a SPORTS BALL SHAPED ABSORBENT URINE PAD as shown and described.

DESCRIPTION

FIG. 1 is an isometric view of a SPORTS BALL SHAPED ABSORBENT URINE PAD showing my new design;

FIG. 2 is a front elevational view thereof;

FIG. 3 is a rear elevational view thereof;

FIG. 4 is a left side elevational view thereof;

FIG. 5 is a right elevational view thereof;

FIG. 6 is a top plan view thereof;

FIG. 7 is a bottom plan view thereof; and

FIG. 8 is my design in an operational setting adhered to boxer shorts.

The broken line showing of boxer shorts in FIG. 8 depicts environmental subject matter which forms no part of the claimed design.

1 Claim, 6 Drawing Sheets
